[57] CLAIM

The ornamental design for a grilled food utensil, as shown and described.

DESCRIPTION

FIG. 1 is a front elevation view of a grilled food utensil showing my new design;

FIG. 2 is a rear elevation view thereof;

FIG. 3 is a left side elevation view thereof;

FIG. 4 is a right side elevation view thereof; and,

FIG. 5 is a top plan view thereof.

The broken line showing of the handle is for illustrative purposes only and forms no part of the claimed design.
